UNITED STATES PATENT OFFICE.

VICTOR R. PAYTON, OF ARDMORE, OKLAHOMA.

RAZOR COMPACT.

Application filed February 2, 1926. Serial No. 85,556.

This invention relates to a shaving outfit, the object of the invention being to arrange the razor, brush and soap in a single container which is made somewhat in the form 5 of a fountain pen, so that the outfit can be easily carried in a pocket or the like of the user.

Another object of the invention is to make the blade adjustable on its handle so that 10 it can be moved to the most convenient position in shaving the face or the neck.

This invention also consists in certain other features of construction and in the combination and arrangement of the several 15 parts, to be hereinafter fully described, illustrated in the accompanying drawings and specifically pointed out in the appended claims.

In describing my invention in detail, reference will be had to the accompanying 20 drawings wherein like characters denote like or corresponding parts throughout the several views, and in which:—

Figure 1 is a longitudinal sectional view 25 through the device, with the parts in closed position.

Figure 2 is a section on line 3—3 of Figure 1.

Figure 3 is a view with the caps removed 30 and showing the razor in folded position in full lines and two other positions in dotted lines.

Figure 4 is a view of the blade supporting member.

35 In these views, 1 indicates the body of the device which is of tubular construction and is provided with an extension 2 of substantially semi-circular form, with its extremity formed with the flat prongs 3 to receive the 40 square part 4 of the blade holder 5 between them. This part is pivotally held between the prongs by the pin 6. The part 5 is of the usual or any desired shape to receive a double edge blade 6 which is held thereon by 45 the clamping member 7 and the set screw 8, these parts being also of the type now on the market or any other desired shape. A spring lever 9 is fastened in the extension 2 and has its free end extending between the 50 prongs 3 to engage the flat edges of the part 4. This arrangement is somewhat like that of a penknife and the edges of part 4 are so formed that the spring lever will hold the leg supporting member 5 in folded position, as shown in Figures 1 and 3, in an inclined position, as shown at A in dotted

lines in Figure 3, or in a straight position, as shown at B in dotted lines in Figure 3. The position A is desirable in shaving the face, while the position B is desirable for 60 shaving the neck. As will be seen, when the blade supporting member is in folded position, it will lie against the extension 2 so that a tubular cap 10 can be placed over the parts to enclose the same, as shown in 65 Figure 1. This cap is provided with female threads to engage the male threads 11 on the cylindrical part of the body 1. The outer end of the cap has a threaded socket to receive the threaded head of a brush 12 for 70 applying lather to the face before shaving and this brush is enclosed by the cap 13 which frictionally engages a part of the cap 10. A ring 14 is adapted to hold the bristles of the brush close together when the 75 brush is not in use, this ring being pushed down against the end of the cap 10 when the brush is to be used.

The outer end of the body 1 is provided with a socket to receive a holder 15 for a 80 piece of soap 16, the holder being movable in the socket through means of the pin 17 working in a slot 18 formed in the body. When the holder is pushed upwardly to draw the soap into the socket, a cap 19 can 85 be placed on the lower end of the body to cover the soap.

A spring holder 20 may be attached to the cap 10 to hold the entire device in the 90 pocket.

From the foregoing, it will be seen that the razor, brush and soap are compactly arranged in a container which may be carried in the pocket of the user. By removing the caps 13 and 19 and projecting the soap 16, 95 lather can be applied to the face in the usual manner and then the cap 10 is removed and the blade supporting member swung outwardly to shaving position. Then the face can be shaved and if it is desired to 100 shave the neck, the supporting member is moved to a straight position, as shown at B in Figure 3 and the neck shaved. After shaving, the set screw 8 is removed to disassemble the blade holding means so that the 105 parts can be cleaned and then the parts are replaced and the blade holder swung into its closed position, as shown in Figure 1. The caps are then put back and then the device may be replaced in the pocket.

110 While the device is mainly designed for traveling men and to be carried in the

pocket, it will, of course, be understood that it can be used by anyone and can be carried in a suitcase or the like.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A razor outfit, comprising a body having an extension at one end thereof, said extension terminating in a pair of prongs, a blade holder having a portion extending between said prongs, a pivot pin passing through the prongs and said portion, a spring lever carried by the extension and having its free end engaging said portion,

said portion having flattened side edges engaged by the spring lever for holding the blade holder in either folded position, in an angular position or in a straight position.

2. A razor outfit, comprising a body having an extension at one end thereof terminating in a pair of prongs, a blade holder having a substantially rectangular shank fitting between the prongs and pivoted thereto, a spring lever carried by the extension and having its free end engaging the flat edges of the shank, means for detachably fastening a blade to the holder, a cap threaded to the body for enclosing the extension and the blade holder when the holder is in folded position.

In testimony whereof I affix my signature.

VICTOR R. PAYTON.
